(57) **CLAIM**

The ornamental design for a toy rack, as shown and described.

DESCRIPTION

FIG. 1 is a top perspective view of a toy rack, showing my design.

FIG. 2 is a bottom perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is a perspective view of the toy rack of FIG. 1 wherein some items are hanging from.

The broken lines showing of the cleaning set, in FIG. 9, depict environmental structure and form no part of the

(Continued)

claimed design. The remaining broken lines depict portions of the toy rack that form no part of the claimed design.

1 Claim, 9 Drawing Sheets
